UNITED STATES PATENT OFFICE.

CHARLES A. LEE, OF SARATOGA SPRINGS, NEW YORK.

DESIGN FOR A CUP.

SPECIFICATION forming part of Design No. 34,859, dated July 30, 1901.

Application filed June 29, 1901. Serial No. 66,616. Term of patent 7 years.

To all whom it may concern:

Be it known that I, CHARLES A. LEE, a citizen of the United States, residing at Saratoga Springs, in the county of Saratoga and State of New York, have invented and produced a new and original Design for Cups, of which the following is a specification, reference being had to the accompanying drawings, forming part thereof, in which—

Figure 1 is a perspective view of my cup; and Figs. 2, 3, and 4 are side elevations of the same, showing the design from various points.

As shown in the aforesaid drawings, the leading or material feature of my design consists of an Indian scene, the foreground of which is an Indian family around a spring, with a tepee or wigwam and forest in the

background. Scrollwork forms a panel surrounding this scene and also forms panels of varying sizes, in which are contained various other pictorial representations. 20

Having described my invention, what I claim as new, and desire to secure by Letters Patent, is—

The design for a cup, as herein shown and 25 described.

In testimony whereof I hereby sign my name to this specification, in the presence of two subscribing witnesses, this 22d day of June, 1901.

CHARLES A. LEE.

Witnesses:

FRANK BUHLES,
H. L. WATERBURY.
